UNITED STATES PATENT OFFICE.

EDWARD L. BUSCHMAN, OF EAST ORANGE, NEW JERSEY.

TRUCK.

1,239,457.

Specification of Letters Patent. Patented Sept. 11, 1917.

Application filed July 29, 1916. Serial No. 111,982.

To all whom it may concern:

Be it known that I, EDWARD L. BUSCHMAN, a citizen of the United States, and a resident of East Orange, in the county of 5 Essex and State of New Jersey, have invented certain new and useful Improvements in Trucks, of which the following is a specification.

The objects of this invention are to provide a truck which, when loaded with a particular article, will indicate whether that article is full weight; to provide such a truck adapted for receiving bags of cement; to accommodate a plurality of such bags of 15 cement or other articles; to indicate as each bag is loaded whether it is of full weight; to thus permit discarding a short weight bag before another is loaded from the bag filling machine; to break the fall of the bags from 20 the machine so as not to break the bags; to employ resilient means for this purpose; to provide a truck which is readily handled; to adapt the truck to be self supporting or manually supported as desired; to provide a 25 strong and durable construction, to secure simplicity of construction and operation, and to obtain other advantages and results as may be brought out in the following description.

30 Referring to the accompanying drawings in which like numerals of reference indicate the same parts throughout the several views,

Figure 1 is a side elevation of a loaded truck embodying my invention;

35 Fig. 2 is a similar side elevation of an unloaded truck folded;

Fig. 3 is a front elevation of the truck open and unloaded;

40 Fig. 4 is a longitudinal section of one of the side members showing the spring and rider mounted therein;

Fig. 5 is a longitudinal section of the rider, and

45 Fig. 6 is a transverse cross-section on line 6—6 of Fig. 4.

In the specific embodiment of the invention illustrated in said drawings, the reference numeral 1 indicates the body portion of a truck frame mounted upon wheels 2, 2 and 50 adapted to be supported in inclined position by a third wheel 3 at the lower end of a prop 4. From the front of the body portion of the frame, that is, the side of the body portion opposite from the prop, projects a tray 55 upon which articles to be transported, such as the bags of cement 6 shown, are placed.

It is to be understood, that the tray is to be considered for convenience, as projecting from the front of the truck, in which case the prop will be seen as arranged at the back 60 of the truck.

Described in greater detail, the frame comprises preferably a pair of separated side members 7, 7 shown as continuously tubular from one end to the other. These 65 side members are held rigidly by a plurality of cross braces 8, shown as bars extending between the side members and looped at their ends over said members and riveted or otherwise held to clamp the loops. At the 70 back of the body portion of the frame are suitable handles 9, 9, the same being shown as riveted to the back of the upper cross brace 8, projecting upwardly and rearwardly therefrom. Preferably, also the 75 material forming the shank of each handle depends below the brace 8 to which it is secured and is looped around a hinge rod 10 which extends transversely of the frame between said depending or looped portions 80 of the handles and projecting beyond the same. Upon these projecting ends of the hinge rod are pivoted the upper ends of spread apart legs 11 of the prop. These legs converge downwardly and, for greater 85 strength, are riveted or otherwise held together near their lower ends, and then spread apart again enough to receive the wheel 3 therebetween.

Preferably, in order to restrict the distance which the prop may swing away from the body portion, a lip 12 projects upward above the hinge rod from each leg adapted to engage the cross brace or side member at the desired position of the prop. For 90 greater rigidity, check means are provided for the prop adjacent the wheel if desired, comprising a jointed arm 13 in the present disclosure, hinged between the legs of the prop on a rivet or the like 14 holding said 95 legs together and also hinged to one of the cross braces of the body portion of the frame, as at 15. Said arm is adapted to bend intermediate of its length upon a hinge pin or rivet 16 so that the prop may be 100 swung toward the body portion of the frame when so desired. Coacting stops 17, 18 are provided on the two portions of the arm adapted to prevent the said portions from being bent past alined position. 105

At the front of both side members of the frame are provided longitudinal slots 19,

19 from the bottoms of said members to about midway of their length. As noted above, the members are hollow, and slidably contained therein are riders 20, there being 5 one rider in each member. The tray 5 is connected to and supported by these riders, the side arms 21, 21 of the tray projecting through the slots and being attached to the riders. Obviously, therefore, by this construction the tray may be moved longitudinally 10 of the side members of the frame. The riders are made long enough to hold the tray in substantially the same angular relation to the side members of the frame 15 at all times. By this construction and because of the definite angle at which the frame is held to the supporting surface by the prop, the tray 5 will always be lowered a given amount for definite weight, because 20 the component of gravity acting parallel to the frame will be proportionate to the actual weight of the load always in the same ratio. It is to be understood, that the tray moves up and down or longitudinally at the front 25 of the frame, and when completely loaded is at the bottom of said frame but does not project beyond the end or below the same, and consequently will not interfere with wheeling the truck around.

30 In order to obtain a free sliding movement of the riders, the same are preferably provided with rollers or the like, and I have shown one such roller 22 near the bottom of each rider adapted to bear against the inner 35 wall of the member opposite the slot. Near the top of the rider are two other rollers 23, 23 arranged to bear against the inner wall of the member adjacent the slot on opposite sides thereof. Obviously a load upon the 40 tray will tend to swing the upper end of the rider forward and the lower end backward, so that the rollers engage the wall of the member and reduce the resistance to sliding of the rider.

45 The rider preferably is provided with a resilient support so that as the load is applied to the tray, the tray is lowered, but returns to its uppermost position when the load is removed. To this end I have shown 50 a spiral spring 24 attached at its lower end to the upper end of the rider, said spring being fixed at the upper end of the member 7 by being hooked into the eye 25 of a cap 26 closing the upper end of said member.

55 Preferably means are provided for indicating whether or not each article is of full weight, and for this purpose scale markings 27 are made upon the members at the point to which the tray should lower for the correct weight of package. For a standard 60 package, such as cement bags shown, short weight can be detected as the bag is loaded. In use it is intended that the bag pass directly from the bag filling machine to the 65 truck, and the workman can remove a bag

immediately which shows by the scale to be of improper weight before another comes from the machine.

In addition to the advantage obtained by the spring support for the tray to check the 70 weights of the bags, the resiliency breaks the fall of the cement bags from the machine to the truck, and particularly breaks the fall of the first bag, and greatly reduces the likelihood of the bag's bursting. 75

Obviously detail modifications and changes may be made in the manufacture of my improved truck without departing from the spirit and scope of the invention and I do not wish to be understood as limiting myself except as required by the following claims when construed in the light of the prior art. 80

Having thus described the invention, what I claim is,

1. In a truck of the character described, a wheeled frame, a load-supporting tray projecting from said frame and connected thereto so as to slide longitudinally of the frame without projecting beyond the end thereof, and springs resiliently supporting said tray. 90

2. In a truck of the character described, a wheeled frame having tubular side members longitudinally slotted, a tray with arms extending into said slots so as to slide thereon, and springs in said tubular side members resiliently supporting said tray. 95

3. In a truck of the character described, a wheeled frame having hollow side members, a tray for supporting a load, riders in said members adapted to support the tray and retain it in the same angular relation to the side members, and springs also in said members for resiliently supporting the 100 riders. 105

4. In a truck, a wheeled frame having hollow side members, a tray for supporting a load, riders in said members adapted to support the tray and retain it in the same angular relation to the side members, said 110 riders having rollers adapted to engage the members and reduce the friction whereby the riders may slide freely, and springs also in said members for resiliently supporting 115 the riders.

5. In a truck, a wheeled frame having hollow side members with longitudinal slots, a tray for supporting a load having its side arms projecting through said slots, riders in the members receiving said arms and thereby supporting the tray in transverse relation to the members, and springs also in said members resiliently supporting the 120 riders whereby the same may slide down in 125 the members as a load is applied to the tray, and will return to uppermost position when the load is removed.

6. In a truck of the character described, a wheeled frame, a tray for supporting a 130

load and adapted to slide longitudinally of the frame when a load is applied, and means for holding said frame at a certain angle to the supporting surface whereby a load of a given weight will always slide the tray to a certain position with respect to the frame under the action of gravity.

5 7. In a truck of the character described, a wheeled frame, a tray for supporting a

load and adapted to slide longitudinally of the frame when a load is applied, and means for holding said frame at a certain angle to the supporting surface whereby a load of a given weight will always slide the tray to a certain position with respect to the frame under the action of gravity, said means being collapsible toward the frame.

EDWARD L. BUSCHMAN.
